APPARATUS FOR EXTRACTION OF ALUMINIUM

Pierre Morize, Venthon, near Albertville, France, assignor to Societe d'Electro-Chimie d'Electro-Metallurgie et des Acieries Electriques d'Ugine, Paris, France, a corporation of France

Application May 5, 1955, Serial No. 506,330

7 Claims. (Cl. 266—35)

The present invention relates to a device for the commercial extraction of aluminium from its alloys or from material in which it is contained.

This device is intended for carrying into effect the known method which consists in the reaction on these alloys or materials, at a suitable temperature, of an aluminium halogenide so as to form a volatile sub-halogenide which is then cooled in a separate chamber in such a way as to cause the separation in the pure state of the aluminium absorbed and the liberation of the initial halogen salt, which is recovered and re-cycled.

This process has, up to the present time, been carried out at a relatively low pressure, which has given rise to difficulties of isolation and fluid-tightness together with the necessity of handling large volumes of gas by reason of the low density of the gases at low pressure.

Finally, since the period of contact of the halogenide with the primary material is short, the necessary balance of concentration of the sub-halogenide cannot be obtained.

The present invention has for its object a device for carrying into effect a process of the kind referred to, this device being designed to overcome the drawbacks mentioned above. Said device essentially comprises an upper tank adapted to contain the molten starting material and forming a reaction chamber closed at its upper portion, its walls being maintained at a temperature equal to or greater than that of the said molten material to be treated, a supply conduit for bringing the aluminium halogenide through a gas-dividing member, one of the faces of which is in contact with the said molten metal, an evacuation pipe for the gaseous sub-halogenides which are formed, located inside the tank and passing through the said tank and the molten material in a fluid-tight manner, a decomposition chamber in which terminates the said evacuation pipe and a tank for receiving pure metal drawn-off from the base of the said decomposition chamber, which is, in addition, provided with a conduit for the recovery of the gases which are formed therein.

The reaction chamber is preferably formed by means of a bell shaped member which plunges into the upper tank. The said bell-shaped member is advantageously provided with double walls providing an internal space adapted to receive a molten metal.

Means are of course provided to obtain the necessary temperatures in the various parts of the apparatus.

The gas-dividing member may be a plug made of porous material, a plate provided with a plurality of holes or a multitubular diffuser.

The present invention is explained below in greater detail with reference to the attached drawings which illustrate various embodiments thereto, and in which:

Fig. 1 is a view in diagrammatic cross-section of a device used in the extraction of aluminium in accordance with the present invention.

Figs. 2 and 3 are alternative forms of embodiment of a device of the kind referred to.

2

In the form illustrated in Fig. 1, the device for extraction of aluminium comprises a tank 1 surmounted by a bell 2 having double walls.

The tank is provided, on the one hand with an orifice 5 closed by means of a porous plug 3 which may also be, for example, a plate pierced with a number of holes or a multitubular diffuser, communicating with a conduit 4 which leads the halogenide to a chamber 5.

On the other hand, a further orifice is formed in the 10 said tank through which is passed an extraction tube 6 made of material which is not attacked by molten aluminium such as, for example, calcined alumina. The tube 6 leads into a chamber 7, the lower part of which constitutes a tank 8 and the upper part is provided with a conduit 9 for evacuating the halogen compound.

The whole assembly comprised by the porous plug 3, the tank 1 and the bell 2, is maintained by heaters 37 at a temperature comprised between 1100° and 1400° C. The chamber 7 and the tank 8 are maintained by a heater 20 38 at a temperature below 1000° C. but above the melting point of aluminium, the tube 4 and the conduit 9 being brought up to a temperature which is at least equal to the temperature at which the vapour tension of the halogen compound is equal to atmospheric pressure.

A liquid metal 10 is provided between the walls of the 25 bell 2. Thus, the liquid starting material employed determines the temperature of the lower portion of the reaction chamber 11, whilst the temperature of the liquid metal 10 determines that of the upper portion, a suitable choice of this temperature enabling the temperatures to be uniformly distributed, thus avoiding premature condensation in the reaction chamber 11.

In addition, the extraction tube 6 passes through the 30 liquid primary material and is thus maintained at the temperature of this latter.

The advantage of an arrangement of the present kind is that it enables the operation to be carried out in a semi-continuous manner. It is actually possible to extract the primary material, whether molten or not, from 35 time to time from the annular space between the bell and the tank and to draw-off from it the residues resulting from the action of the halogen compound on the primary material.

In the same way, it is possible to take off from the tank 45 8 the quantities of pure aluminium so formed, within the limits necessary to maintain a suitable level of this liquid metal in the chamber 7.

Fig. 2 shows an alternative form of embodiment in which the tank 21 of refractory material, such as 50 90% Al_2O_3 —10% SiO_2 , for example, is provided with a bell 22 of the same material. The tank is pierced with a single orifice closed by means of a porous plug 23 through which the halogen compound is passed through the medium of an iron tube 24, into the chamber 25 which is furthermore limited by a metal plug 21c, for example of molten lead, resting on a bed 21a, the nature of which will be defined below.

An extraction tube 26 of, for example, calcined alumina, leads into a chamber 27 through a plug 27a and a joint 27b; at the lower part of the chamber is provided a tank 28, of graphite for example, from which the halogen compound can pass out at 29 and can be re-cycled at 30.

The tank 21 is supported on an insulating bed 21a contained in a plate 21b, said bed being of granulated heat-insulating material.

In Fig. 3, the tank 31 of refractory material (90% 55 Al_2O_3 —10% SiO_2 for example), is provided with a bell 32 of the same material. The tank is pierced with an orifice provided with a porous plug 33, through which passes the halogen compound which is led through an iron tube 34 into the chamber 35, the walls of which

3

are made of aluminous porcelain and which pass through a plug 35a and a joint 35b.

The extraction tube 36 is of calcined alumina and enables the sub-halogenide to be evacuated, the halogenide being re-cycled as previously described, from a chamber formed above a tank (not shown) in which are collected respectively the halogen compound and the pure aluminium product.

It will be seen that in all the forms of embodiment shown (comprising a tank with a flat base, a raised base or a base with a depression) there has been provided a fluid-tight passage for the tube which evacuates the sub-halogenides formed.

In Fig. 1, the molten metal contained in the tank 1 itself serves as a point providing the fluid-tight passage of the evacuation tube 6 into the tank 7.

In Fig. 2, the molten metal contained in the tank 21, the molten lead 21c and the joint 27b ensure in combination the fluid-tight passage of the conduit 26.

In Fig. 3, the molten metal contained in the tank 31 and the joint 35b carry out the same function.

In Figs. 2 and 3, the arrangements for maintaining the temperature of the upper tank have not been shown and the details of the bell have also not been described, the latter being preferably a bell with double walls identical with that of Fig. 1.

In all the devices shown, the process is as follows: The halogen compound passes through the porous plug from the bottom to the top, the necessary pressure being applied to it to that end, and bubbles into the molten primary material. The sub-halogenide which results from the reaction is collected in the upper portion of the bell and passes into a decomposition chamber at the base of which is collected the liquid pure aluminium which forms in the tank provided for that purpose.

There are given below, by way of example, some results of the treatment carried out in the devices shown in Figs. 1 and 2.

Example 1

Using the device shown in Fig. 1, a bath of metal to be purified was heated to 1250° C. for 3 hours 30 minutes, and through this bath 275 grams of aluminium chloride were passed. 42 grams of pure aluminium were subsequently collected and the efficiency of the operation amounted to 38%.

Example 2

Using the arrangement shown in Fig. 2, a bath of metal to be purified was heated to 1200° C. for 5 hours, and through this metal bath was passed 370 grams of aluminium chloride. 45 grams of pure aluminium were collected and the efficiency of the operation was 30%.

What we claim is:

1. An apparatus for commercial extraction of aluminium from aluminum containing alloys or like materials, comprising an upper tank adapted to contain the starting material in a molten state up to a given level, forming a reaction chamber having a gas-tight upper part, means for heating said tank, a supply conduit adapted to be connected to a source of aluminum halogenide opening in the lower part of said tank through a gas-dividing member, an evacuation pipe passing through said tank in a fluid-tight manner and having an upper end opening in the upper part of said reaction chamber above the level of the starting material therein, and a lower end opening in a gas-tight decomposition chamber, a gas draw-off pipe opening in said decomposition chamber and a draw-off tank connected to said decomposition chamber beneath said chamber, means being provided for heating said decomposition chamber and draw-off tank.

2. An apparatus for commercial extraction of aluminium from aluminum containing alloys or like materials, comprising an upper tank adapted to contain the

starting material in a molten state up to a given level and having an open upper part, a bell-shaped container having lateral walls extending downwards into said tank through said open upper part, below said level of said starting material, thereby forming a reaction chamber within said tank, means for heating said tank and said bell-shaped member, a supply conduit adapted to be connected to a source of aluminum halogenide opening in the lower part of said tank through a gas-dividing member, an evacuation pipe passing through said tank in a fluid-tight manner and having an upper end opening in the upper part of said reaction chamber above the level of the starting material thereinto, and a lower end opening in a gas-tight decomposition chamber, a gas draw-off pipe opening in said decomposition chamber and a draw-off tank connected to said decomposition chamber beneath said chamber, means being provided for heating said decomposition chamber and draw-off tank.

3. An apparatus as claimed in claim 1, in which said lateral walls of said bell-shaped member are double walls providing an internal space adapted to receive a molten metal.

4. An apparatus for commercial extraction of aluminum from aluminum containing alloys or like materials, comprising an upper tank adapted to contain the starting material in a molten state up to a given level and having an open upper part, and a substantially flat bottom provided with a first and second opening, a bell shaped container having lateral double walls providing an internal space adapted to receive a molten metal and extending downwards into said tank through said open upper part, below said level of said starting material, thereby forming a reaction chamber within said tank, means for heating said tank and said bell-shaped member, a gas-dividing member tightly fitted in said first opening, a supply conduit having one end adapted to be connected to a source of aluminum halogenide and another end opening under said gas-dividing member and tightly connected to the bottom of said tank, an evacuation pipe passing through said second opening in a fluid tight manner and having an upper end opening in the lower part of said tank through a gas-dividing member, an evacuation pipe passing through said tank in a fluid-tight manner and having an upper end opening in the upper part of said reaction chamber above the level of the starting material therein, and a lower end opening in a gas-tight decomposition chamber, a gas draw-off pipe opening in said decomposition chamber and a draw-off tank connected to said decomposition chamber beneath said chamber, means being provided for heating said decomposition chamber and draw-off tank.

5. An apparatus for commercial extraction of aluminum from aluminum containing alloys or like materials, comprising an upper tank adapted to contain the starting material in a molten state up to a given level, and having an open upper part, a bottom with a central raised portion encircling a single opening having walls extending substantially vertically, a bell-shaped container having lateral double walls providing an internal space adapted to receive a molten metal and extending downwards into said tank through said open upper part and resting upon said central raised portion of the bottom of said tank, an annular gas-dividing member tightly fitted in said single opening in said raised portion of the bottom of said tank and having a substantially central opening, a supply conduit having one end adapted to be connected to a source of aluminum halogenide and another end opening under said gas dividing member and extending substantially axially between the walls of said single opening in said raised portion, an annular plug between said conduit and said walls of said single opening, an evacuation pipe arranged substantially axially in said conduit and passing tightly through said central opening in said gas-dividing member, said evacuation pipe having an upper end opening in the lower part of said tank through a gas-dividing

member, an evacuation pipe passing through said tank in a fluid-tight manner and having an upper end opening in the upper part of said reaction chamber above the level of the starting material therein, and a lower end opening in a gas-tight decomposition chamber, a gas draw-off pipe opening in said decomposition chamber and a draw-off tank connected to said decomposition chamber beneath said chamber, means being provided for heating said decomposition chamber and draw-off tank.

6. An apparatus as claimed in claim 5, in which the bottom of said upper tank is supported on a bed of granular, heat insulating material carried in a shallow circular tray having an opening for the passage of said supply conduit, said granular material also serving as a support for said annular plug.

7. An apparatus for commercial extraction of aluminum from aluminum containing alloys or like materials, comprising an upper tank adapted to contain the starting material in a molten state up to a given level and having an open upper part and a bottom with a downwardly projecting, central portion contained by lateral walls of substantial depth and thickness and providing a single, central opening in said bottom, a bell-shaped container having lateral double walls providing an internal space adapted to receive a molten metal and ex-

tending downwards into said tank through said open upper part and resting on said lateral walls of said central portion, a supply conduit having one end adapted to be connected to a source of aluminum halogenide and another end tightly fitting in said opening in the bottom of the tank, an annular gas-dividing member tightly fitted in said other end of said conduit and having a substantially central opening, an evacuation pipe arranged substantially axially in said conduit and passing tightly through said central opening in said gas-dividing member, said evacuation pipe having an upper end opening in the lower part of said tank through a gas-dividing member, an evacuation pipe passing through said tank in a fluid-tight manner and having an upper end opening in the upper part of said reaction chamber above the level of the starting material therein, and a lower end opening in a gas-tight decomposition chamber, a gas draw-off pipe opening in said decomposition chamber and a draw-off tank connected to said decomposition chamber beneath said chamber, means being provided for heating said decomposition chamber and draw-off tank.
